United States Patent

Des. 236,016
Patented July 22, 1975

236,016

STILT

Peter F. Boyce, 118 E. Rio Grande Ave.,
Wildwood, N.J. 08260

Original design application Apr. 25, 1972, Ser. No.
247,506, now abandoned. Divided and this application Oct. 3, 1972, Ser. No. 294,542

Term of patent 14 years

Int. Cl. D21—04

U.S. Cl. D34—14 E

FIG. 1 is a front perspective view of a stilt showing my new design;

FIG. 2 is an enlarged side perspective view thereof with the upper handle portion omitted for convenience of illustration;

FIG. 3 is a rear elevational view of FIG. 2;

FIG. 4 is a bottom plan view thereof;

FIG. 5 is a longitudinal cross-sectional view thereof as taken from line 5—5 of FIG. 4.

This is a division of Ser. No. 247,506, filed Apr. 25, 1972, and now abandoned.

I claim:

The ornamental design for a stilt, as shown and described.
